UNITED STATES PATENT OFFICE.

EDMUND BECKER, OF WASHINGTON, DISTRICT OF COLUMBIA.

CONCRETE-FORM.

1,191,492.

Specification of Letters Patent.

Patented July 18, 1916.

Application filed April 23, 1910. Serial No. 557,280.

To all whom it may concern:

Be it known that I, EDMUND BECKER, a citizen of the United States, residing at Washington, in the District of Columbia, have invented certain new and useful Improvements in Concrete-Forms, of which the following is a specification.

My invention relates to a novel type of mold or form to be used in casting monolithic concrete walls, and it consists in a special combination and arrangement of mold parts adapted to permit of the extensive use of externally and lightly tacked but otherwise solidly supported frame members, in combination with a plastered and smoothly troweled porous mold lining to be built and finished in position of use, but before completion of the opposite heavier lining which is finished last and held in place by external tacking. The framework is, moreover, combined to facilitate the lathing and plastering operations and so as to permit of very extensive use of externally and only partly driven nails or so-called "tacking" so as to injure the lumber as little as possible, saving it for future use and greatly facilitating the process of form removal, which is already considerably simplified by the use of the easily destroyed plaster lining. Projecting nails cannot, of course, be used inside of the mold, hence the necessity of using a special construction the permits of using relatively weak and externally driven fasteners.

One preferred form of my invention, in which over ninety five per cent. of the frame fasteners are externally and only partly driven nails, all other fasteners being bolts, is illustrated in the accompanying drawings, in which:

- 40 Figure 1 is a horizontal section of a form showing front plaster lining C and rear plank lining D, the plane of section being at the level indicated by plane 1 to 2 running horizontally through Figs. 2 to 5. Fig. 2 is an outside elevation of a part of the front wall as seen looking in the direction of arrow I in Fig. 1. Fig. 3 is an inside elevation of a part of the front unplastered lathing as seen looking in the direction of arrow II in Fig. 1. Fig. 4 is an external elevation of a part of the rear wall as seen looking in the direction of arrow III in Fig. 1. Fig. 5 is an internal elevation of a part of the rear wall as seen looking in the direction of arrow IV of Fig. 1. Fig. 6 is a perspective view of a plank lining tacked by hasps to

the posts and studding. Fig. 7 shows one of the planks with the hasps hinged in order that they may be flattened down for transportation and storage. Fig. 8 shows a horizontal section of Fig. 9, and Fig. 9 the perspective view of a wall with a portion lathed and plastered. Fig. 10 is a perspective view of the framing as it appears before any lining has been applied. Fig. 11 is a vertical transverse section of the form showing the front plaster lining C, the rear plank lining D and a part of the east wall A, all externally tacked nails, that is to say, nails that are only partly driven being indicated by t.

Referring to Fig. 10, sills W, spaced the desired distance apart, are placed on the footing V. Upright members, or main posts, E are erected and stayed (stays not shown), and united by temporary spreader-ties F. These ties, Fig. 11, are prepared in lots ready-bored with a series of suitably spaced holes for bolts f, to provide beforehand for the different standard wall thicknesses or standard depths of forms. The stringer planks G, are then tacked to the upright members E and the intermediate upright members, or filling studs, H are spaced and tacked to stringer plank G at their proper places. The stringer, or wall piece, I, resting on spreaders F is then secured to the upright members E by tie-bolts K inserted through the upright members E. The framing being completed, the next step is to line the form, having due regard to the desired finish to be obtained. By reference to Figs. 2, 3, 8 and 9 the various steps in finishing a form in order to obtain a smooth or ornamental surface are disclosed. The upright members E and H are lathed with metal or wooden laths l which constitute the preliminary lining of the front or finished wall of the form, and is designated by C in Figs. 2 and 3. The laths are then covered or lined with a coat of plastic material troweled smooth or finished in the desired ornamental design as indicated by L, Figs. 8 and 9. The construction of a form as thus described allows me to retard the setting of the surface of the concrete after pouring in a quick, effective and economical manner by playing a hose on the back of the lathing, thus soaking the plastering of the form, which, being somewhat porous and permeable, absorbs and distributes the water evenly on the surface of the concrete. This result cannot be obtained by the use of wooden lagging, as the moisture

would not be evenly distributed and would ultimately deform and destroy the wood.

The best and least expensive method of obtaining a rough finish is by the use of a plank lining D, as shown in Figs. 4, 5 and 6, a detail of the plank M being shown in Fig. 7. The planks should be planed to the same thickness and the edges trueed so as to superpose tightly to prevent the oozing of the concrete through the joints, and are secured to the upright members E and H, Fig. 6, by means of hasps b, Fig. 7, one leaf of which is securely fastened to plank M and the other tacked to the upright members E and H. These planks are used in their entire length as purchased and are interchangeable and continuous. In actual practice I have found that the edges of the planking described may be packed with felt instead of being trueed as mentioned above. It may be remarked in this connection that the linings C and D just described add greatly to the strength and rigidity of the form. Figs. 1, 2, 4 and 5 show the upright members of the back wall spaced at greater intervals than those of the front wall because of the greater stiffness of the planks M, and at the same time this construction allows easier access to the plasterer into the form for coating the front wall and also to the concrete gang for pouring the concrete, the rough planking being put in place only as the filling progresses. As the work progresses upwardly, the function of the spreader tie is performed by the concrete filling so that when the level of such filling comes close to such a tie as shown in Fig. 11 the tie is removed. When the concrete in the forms has set, the tie-bolts K are unscrewed, the stringer, or waling piece, I lowered, the upright members released from stringer plank G, whereupon the upright members of the form, together with the lathing and plastering of the front wall, fall away from the finished face, leaving the wall perfect and free of blemishes, the holes h left by the tie-bolts K being filled with concrete of the right grain and color while deforming.

I claim:

1. A mold for casting monolithic concrete walls comprising a front mold wall and a rear mold wall, said front mold wall being a lath and plaster partition adapted to form externally projecting and closely set mortar keys to provide capillary ingress for water applied externally to modify the setting process.

2. A mold for casting monolithic concrete walls comprising a front mold wall and a rear mold wall, said front mold wall being a lath and plaster partition; and said rear mold wall being formed of widely spaced studs and comparatively heavy sheeting to provide access through its said spaced studs for building the said lath and plaster partition in position of use.

3. In a temporary wall for a mold to be used for casting monolithic concrete walls, a wooden framework comprising the combination with heavy vertical timbers or posts E spaced at relatively great intervals, 70 and heavy horizontal timbers or wale-pieces I bolted externally to said vertical timbers to constitute therewith the fundamental heavy bolted frame of the wall; of a lighter secondary "tacked" framework supported 75 and resting in the said heavier bolted frame and consisting of a series of relatively thin uprights or studs H arranged at proper intervals between said heavy posts E to bear outwardly against said heavy wale-pieces I; 80 and relatively thin external horizontal stringer planks G "tacked" externally first to said posts E and then to said studs H, the depth of said studs and posts being the same to form an inside discontinuous but solid 85 and even bearing face for a suitable lining.

4. In a temporary wall for a mold to be used for casting monolithic concrete walls, a wooden framework comprising the combination with heavy vertical timbers or 90 posts E spaced at relatively great intervals, and heavy horizontal timbers or wale-pieces I bolted externally to said vertical timbers to constitute therewith the fundamental heavy bolted frame of the wall; of a lighter 95 secondary "tacked" framework supported and resting in the said heavier bolted frame and consisting of a series of relatively thin uprights or studs H arranged at proper intervals between said heavy posts E to bear outwardly against said heavy wale-pieces I; 100 and relatively thin external horizontal stringer planks G "tacked" externally first to said posts E and then to said studs H; the depth of said studs and posts being the 105 same to form an inside discontinuous but solid and even bearing face for a suitable lining; said lining consisting in a lath supported plastic lining built directly upon such discontinuous face in a manner similar to 110 that used in common house partition plastering.

5. In the framework for the temporary walls of a mold used for casting a monolithic concrete wall, the combination with two equal 115 and oppositely arranged fundamental frames each composed of heavy vertical posts and external horizontal wale-pieces; of a horizontal transverse adjustable bond for connecting and spacing the opposite mold walls 120 at every crossing point of the said heavy timbers in the one wall with the opposite crossing point of the heavy timbers in the opposite wall; such bond comprising a temporary space-gaging spreader-tie bolted 125 laterally to the said vertical posts and a permanent space holding clamp bolt passed centrally through said four heavy timbers; said spreader-tie being sufficiently long to project in support of the said external wale- 130

pieces, also having a series of bolt holes to permit of regulating the depth of the mold for any standard size of concrete wall.

6. In a mold for casting monolithic concrete walls, the combination with inside tacked lath and plaster lining; of a rear wall composed of open stud and post framing and externally fastened inside plank lining, said rear studding being made open to afford 10 free access for internally lathing and plas-

tering said front wall, and said plank lining being held in place by external tacking.

In testimony whereof, I have signed my name to this specification in the presence of two subscribing witnesses.

EDMUND BECKER.

pieces, also having a series of bolt holes to permit of regulating the depth of the mold for any standard size of concrete wall.

6. In a mold for casting monolithic concrete walls, the combination with inside tacked lath and plaster lining; of a rear wall composed of open stud and post framing and externally fastened inside plank lining, said rear studding being made open to afford 10 free access for internally lathing and plas-

tering said front wall, and said plank lining being held in place by external tacking.

In testimony whereof, I have signed my name to this specification in the presence of two subscribing witnesses.

Corrections in Letters Patent No. 1,191,492.

It is hereby certified that in Letters Patent No. 1,191,492, granted July 18, 1916, upon the application of Edmund Becker, of Washington, District of Columbia, for an improvement in "Concrete-Forms," errors appear in the printed specification requiring correction as follows: Page 1, line 32, for the word "the" read *that*; same page, line 85, for the word "wall" read *wale*; page 2, line 108, claim 4, for the word "latch" read *lath*; and that the said Letters Patent should be read with these corrections therein that the same may conform to the record of the case in the Patent Office.

Signed and sealed this 22d day of August, A. D., 1916.

[SEAL.]

F. W. H. CLAY,

Acting Commissioner of Patents.
